United States Patent Office

Des. 193,636
Patented Sept. 18, 1962

193,636

BOTTLE

John Jay Anderson, Kenosha, Wis., assignor to
S. C. Johnson & Son, Racine, Wis.

Filed Oct. 20, 1960, Ser. No. 62,549

Term of patent 14 years

(Cl. D58—6)

Fig. 1.

Fig. 4.

Fig. 2.

Fig. 3.

Fig. 5.

The rear and side not shown are the same as the respective front and side shown.

I claim:

The ornamental design for a bottle, as shown and described.
